UNITED STATES PATENT OFFICE.

HORACE DUMARS, OF NEW SUFFOLK, NEW YORK.

ADVERTISING DISPLAY-MACHINE.

1,253,220.

Specification of Letters Patent. Patented Jan. 15, 1918.

Application filed June 3, 1915. Serial No. 31,880.

To all whom it may concern:

Be it known that I, HORACE DUMARS, a citizen of the United States, and a resident of New Suffolk, New York, have made Improvements in Advertising Display-Machines, of which the following is a specification.

The invention relates to machines for automatically displaying and changing pictures or like matter for advertising or amusement purposes. The objects and advantages of the invention will be set forth hereinafter in part, and in part will be obvious herefrom.

15 The invention consists in the novel parts, constructions, arrangements, combinations and improvements herein shown and described.

20 The accompanying drawings herein referred to and constituting a part hereof, illustrate one embodiment of the invention, and together with the description, serve to explain the principles thereof.

25 Of the drawings:—

Figure 1 is a side elevation of a machine constructed in accordance with the principles of the invention and utilized as a projecting apparatus;

30 Fig. 2 is a side elevation similar to Fig. 1 showing the machine used as a reflecting apparatus;

Fig. 3 is a side elevation looking at Fig. 1 from the back;

35 Fig. 4 is a horizontal section on the line A—B of Fig. 1;

Fig. 5 is a horizontal section on the line C—D of Fig. 2;

Fig. 6 is a vertical section on the line E—F of Fig. 3; and

40 Fig. 7 is an enlargement of a portion of the central part of Fig. 5, showing the lamp house with the lamps and reflectors in the open position.

In accordance with certain features of the invention, a machine is provided especially adapted for advertising and also for amusement purposes, and in certain aspects having in mind more especially automatically operating machines for exposing successive pictures to view for a desired interval of time, which machines are adaptable or capable of projecting the light through a film, and of reproducing pictures and other matter by reflected light.

45 50 55 In certain aspects of the invention, a machine is provided adapted to use endless

bands of film or of opaque material bearing pictures or other matter which are reproduced by reflected light, and in the present embodiment these various features are real- 60 ized together in one machine.

The invention, in one feature thereof, prevents or eliminates a dangerous amount of heat in the neighborhood of the film, thereby rendering it entirely practicable to permit 65 the machine to run on for protracted periods of time without watching or testing as to the amount of heat evolved, as would ordinarily be necessary to avoid ignition or explosion of inflammable film. Other features of the invention, and advantages flowing therefrom will appear hereinafter or be obvious herefrom.

Referring more particularly to the embodiment illustrated herein by way of example, a machine is provided with a suitable frame comprising a base or foot plate 1, adapted to rest upon a support, from which foot plate extends upwardly the apertured frame piece 2, having the horizontal 70 member 3 extending along the top thereof. This frame may be integral if desired, and will be of suitable material and construction. In the form shown, if the base be firmly held, the whole machine is maintained in stable 75 80 85 position.

Mounted on a cross piece 4 of the frame in bosses 5 and 6 are rods 7 and 8, upon which rods a lamp housing, which may also carry the whole or a part of the lenses may be 90 detachably mounted. Coöperating with the supports just described, are provided lamp and lens housings interchangeable the one with the other, whereby the machine may be used either for direct projection or for 95 reflection.

In coöperative juxtaposition with the interchangeable lamp and lens housing are devices for feeding the endless band of film or other matter to be illuminated and illustrated, whether by direct projection or by reflection, although in certain features of the invention other forms than the endless band may be employed. Whether a strip or band for projection or reflection be employed, it 100 105 will be styled herein for convenience a film band.

In the embodied form there are provided along the top frame piece 3 a series of driven rolls 10, 11, 12, 13 and 14, some or all of which 110 engage the film band by positive means, as for example sprocket teeth 15 engaging with

WEIGHING-SCALE.

1,253,239.

Specification of Letters Patent. Patented Jan. 15, 1918.

Application filed January 27, 1913. Serial No. 744,443.

To all whom it may concern:

Be it known that I, CLARENCE H. HAPGOOD, a citizen of the United States, residing at Toledo, county of Lucas, and State of Ohio, have invented certain new and useful Improvements in Weighing-Scales, of which the following is a specification.

In the accompanying drawings I have shown my invention as applied to a computing scale of the pendulum type with a drum chart or price indicator, but it will be understood that it is applicable to other forms of scale with or without modification; and though the precise form of the invention disclosed is that preferred by me, it is shown and described for the purpose of illustration only, and my invention is capable of many modifications in respect thereto all coming within the scope of the following claims which are intended to distinguish my invention from what is old in the art, without, however, abandoning or dedicating to the public any part thereof.

Referring to the accompanying drawings forming part of this application, Figure 1 is a side elevation partly in section of a pendulum scale with a computing cylinder, embodying my invention; Fig. 2 a front elevation thereof; Fig. 3 a rear elevation partly in section on the vertical plane of the line 3—3 of Fig. 1; Figs. 4 and 5 side and front elevations respectively of a detail to be described later; Fig. 6 an enlarged transverse section on the line 6—6 of Fig. 2; Fig. 7 an enlarged side elevation of the connecting member between the scale beam and the computing chart cylinder; Fig. 8 a fragmentary view of the upper end of the same at right angles to the plane of Fig. 7; Fig. 9 a similar view of the lower end of the connection; Figs. 10 and 11 perspectives of certain details to be described later; Figs. 12 and 13 fragmentary side elevations from opposite sides of an improved check link connection forming part of my invention; Fig. 14 a plan view partly in section of the same; Fig. 15 an end view thereof; Fig. 16 a detail in perspective; Fig. 17 is an elevation on the plane of Fig. 3 of the connection between the beam and the pendulum structure shown in said figure; Fig. 18 is an elevation of the same parts taken at right angles to the plane of Fig. 17; Fig. 19 is a fragmentary section of the end of the beam showing the mounting of the knife edge pivot; Fig. 20

is a side elevation and Fig. 21 a perspective of the knife edge detached; Figs. 22 and 23 are elevations and longitudinal sections respectively of the agate for co-operating with said knife edge and its immediate support. 60

Referring now particularly to Figs. 1, 2, 3, I will first describe briefly the more prominent features and elements of the scale to which my invention has been applied. Upon the scale base 18 at one end thereof, 65 is mounted a fulcrum horn 19 which carries the scale lever 20, and at the other a housing 21 which contains the automatic load counterbalancing mechanism and is surrounded by a cylindrical casing 22 containing the cylindrical computing chart. Upon the beam 20 is mounted the usual platform 23 for receiving the material to be weighed and from the spider 24 of the same extends the check rod 25 connected by the check link 75 26, to be described later in detail, with the stationary check post 27 within the hollow base. At 28 is shown a dash-pot.

The longer end of the scale lever 20 extends through an opening 29 into the housing 21 before mentioned, where it is connected by a stirrup 31, strap 32 and segment 33 with a pendulum load off-setting means 34. The stirrup 31 is of novel construction comprising a socket member 106 which is 80 longitudinally bored at 107 to form a socket for the shank 108 of an agate supporting member 109. The upper end of the socket 107 is reduced and tapped at 110 to receive the correspondingly reduced and threaded upper 85 end of the shank 108 and the lower end of the socket member is split at 111 and formed with laterally projecting ears 112—112 which receive screws 113—113 to clamp or draw the members of the socket around the 90 shank 108. By this means it will be seen that the effective length of the member 31 may be adjusted as desired. The shank 108 is provided with a milled head 114 for manipulating the same and the agate supporting frame 109 is swiveled thereto by the headed bolt or rivet 115. The frame 109 is struck up out of sheet metal and comprises the legs or branches 116—116 and an intermediate wide portion 117 through which the 100 supporting pivot 115 extends, and the lower ends of the branches 116—116 are inwardly turned as at 117—117 to support a U-shaped plate or trough 118 which receives the agate, the ends of said trough abutting against the 105 110

side members or legs of the frame. The bottom 119 of the trough is formed with a transverse corrugation or rib 120 upon which rests the agate 121 so that the latter is capable of a limited tilting movement but is prevented from lateral movements by the sides of the trough and from extended longitudinal movement by the legs of the frame. The upper edges of the trough are inwardly bent as seen at 122—122 in Fig. 23 to retain the agate against vertical movement.

The nose or end 123 of the scale beam is perforated as at 124 (see Fig. 20) and formed with a cross groove 125 in register 15 with the perforation to receive a knife edged pivot 126 which is tapped at the back (see 127, Figs. 21 and 22) to receive the end of a screw 128 extending through the perforation in the beam end and securing the knife 20 edge thereto. The knife is chamfered or cut away at its opposite ends 129—129 so that any end contact that it may have with the frame 109 will be only at the extreme edge of the knife and will not therefore furnish 25 much friction. The cotter pin 130 provided with a knurled head 131 extends between the legs of the frame 109 above the beam end to prevent the knife edge leaving the agate. When it is desired to remove the stirrup 30 from the beam it is necessary only to withdraw the cotter pin when the frame 109 furnishes ample space for the purpose. It will be readily seen that by this construction the agate is free to adjust itself to 35 conform to the knife edge automatically and the parts are readily assembled and associated when required.

The load off-setting means is suspended by knife edges 35 from brackets 36 within 40 the housing, and is adjustable relatively to the segment which is pivoted at 34 thereon by set screws 35'—35' tapped into the pendulum head and bearing against the edge of the segment. The scale lever or beam 45 is also formed with a laterally extending arm 37 to which is attached by means to be described more in detail later a connecting rod 38 which carries a rack 39 for turning the cylinder chart 40 through the medium 50 of the pinion 41 upon the arbor or shaft thereof. The rod 38 above referred to extends through a hollow column 42 of which there are two shown connecting the housing with the chart casing, and the latter rests 55 upon a casting 43 supported by brackets 44—44 extending upwardly from the housing.

The cylinder or drum shaft extends 60 through openings 45 formed in the ends of the casing and rests upon anti-friction disks 46—46 pivoted in brackets 47—47 upon the exterior of the casing, the whole being covered by end plates 48—48 secured to the casing. From the brackets 47—47 extend 65 additional brackets 49—49 which are bent in-

wardly over the ends of the cylinder shaft and carry screws 50—50 which are adjusted to prevent vertical displacement of the shaft. Other screws 51—51 extending through the brackets in a horizontal direction serve to 70 prevent endwise movement of the shaft. As shown in Fig. 1, the casing is provided with front and rear side openings 52—53 for inspection and reading of the chart by the operator and the purchaser respectively. 75

The invention which forms the subject matter of the claims of this application will now be described in connection with the scale briefly set forth in the foregoing paragraphs. In order to secure a connection between the rotary chart and scale beam which shall be as nearly frictionless as possible, and therefore not interfere with the accuracy of the reading of the scale, I have perfected a novel construction of rack rod for 80 meshing with the pinion of the former, the novelty relating in part to the form of connection between the rod and the lever. At its lower end the rack rod 38 is screwed into a split sleeve 54 by which it is tightly secured, and a U-shaped leaf spring is clamped between the lower end of said sleeve and a nut 56 screwed upon the projecting end of the threaded rod, the other end of the leaf spring being clamped between a casting 59 85 and a sheet metal plate 60 secured to the casting by screws 60'—60', and forming part of the means by which the casting is connected to the lever, as will be now described. (See Figs. 7—11 inclusive). - plate 60 upon the upwardly directed knife edges, but in case of a sudden downward movement of the lever or upward movement of the rack rod, the screw 74 will bear 5 upon the downwardly directed knife edge 67 and prevent displacement of the parts but without interfering at all with the relative rotation of the parts, it being observed that the terminal and intermediate knife edges 10 are in the same horizontal line.
- At its upper end the rack rod 38 is shouldered as at 76 and a strap 77 secured thereto which at its upper end 78 is bent laterally and perforated to receive a threaded shank 15 79 of a rack 80. The latter depends from the end 78 of the strap and is loosely held thereto by a conical nut 81, the opening in the strap being sufficiently large to allow some play or lateral movement of the shank 20 79. A lock nut 82 is also screwed upon the shank 79 for its common purpose. It will thus be seen that the rack 80 depends from the upper end of the strip 77 and is free to move with relation thereto, though its side- 25 wise movement is limited by pins 83—83 projecting from the strap 77 (see Fig. 8). By reason of this suspension of the rack with the limited play, any binding between the rack and the pinion which might be caused 30 by a slight displacement of either one or the other from its correct position is avoided, since the rack is free to yield and accommodate itself to the pinion, and yet tends to return to its proper position.
- 35 The casting 59 above referred to, as secured to the lower end of the rack rod by the leaf spring, is overweighted on the toothed side of the rack as at 84, in order to hold the rack yieldingly in engagement 40 with its pinion. By the construction above described I practically eliminate all the friction in the connection between the scale beam and the cylinder chart and therefor get rid of any error or inaccuracy from this source.
- 45 Turning now to Figs. 1 and 13 to 17 inclusive, I will describe the improved form of check link by which I reduce the friction commonly found in this part of scales. The lower ends of a stationary post 27 and 50 check rod 25 are normally at about the same level and to the lower end of each is screwed or otherwise fastened a knife plate 85 which is generally rectangular in section but provided at diagonally opposite corners with 55 parallel ears 86—86 which are formed with oppositely directed knife edges 87—88. The knife edges 87—87 upon one side of the pair of posts are directed toward each other and those 88—88 upon the opposite side are directed away from each other. A thrust member 89 having open end seats 90—90 extends between the knife edges 87—87, and a tension member 91 having eyes 92—92 embraces the knife edges 88—88 so that a 60 movement of the posts toward each other is checked by the thrust bar 89, and a movement away from each other prevented by the tension bar 91. The two bars or members of the link are held and pivoted together by a screw bolt 93 provided with a 70 nut 94 and spaced apart by a sleeve 95 surrounding said bolt. With a check device constructed as above described, the members are free to move with respect to each other and any slight twist or lateral displacement 75 with reference to each other has no material effect upon the friction between the parts.
- Turning now to Figs. 1, 2, 4, 5, and 6, I will describe a device shown therein for conveniently indicating the prices of various 80 commodities in convenient relation to the computing chart. Immediately in front of and below the horizontal sight opening upon the salesman's side of the chart casing, I mount a horizontal rod 96 supported in ears 85 97—97 projecting from the casing and upon which a small casting or castings 98 (see Fig. 6) are free to be moved longitudinally of the rod and set in any desired position by a set screw 99. The casting carries an upwardly projecting ear 100 upon which is mounted a pointer 101 which may be brought into registry with any of the price indications 102 upon the lower edge of the sight opening. At its lower end the casting 95 98 is formed with an eye 103 for the reception of the hook 104 of a tag 105 bearing the name of any commodity which is designed to be sold with the aid of the scale in question. Each of these tags, which are best shown in 100 Fig. 5 of the drawings, is provided at its lower edge with an opening into which may be inserted the hook of another tag so that any desired number of tags bearing the names of different commodities may be suspended from a single slide or casting. Obviously any number of these slides 98 may be used, though in Fig. 2 of the drawings I have shown but two of them. In case the operator or salesman is forgetful or uninformed as to the prices of various commodities and especially in the case of commodities whose prices fluctuate from day to day, the tags suspended from the several slides 105 which are properly positioned according to 110 the price of the commodity form an efficient means of refreshing the memory of the salesman.
- 115 I claim:
1. A weighing scale comprising a beam, 120 load-counterbalancing mechanism connected thereto, a rotary indicator mounted above the beam and load-counterbalancing mechanism, a pinion upon the shaft of said indicator, a rack rod connected to said beam 125 and extending above the pinion, a rack suspended from the upper end of said rack and side stops upon the rack-rod for limiting the sidewise movement of the rack rod.
  2. In a scale comprising a beam and a 130

rotary indicator, a rack rod connected to the beam and laterally extended at its upper end, a rack depending at its upper end from said lateral extension, means for limiting 5 sidewise movement of the rack, and means for loosely and adjustably securing it in said lateral extension.

3. In a scale having a beam and rotary indicator, a pinion upon the shaft of said indicator, a rack rod connected to the beam extending upward therefrom and provided with a lateral offset, a rack having a reduced shank loosely extending through said offset and a nut engaging said shank.

15 4. In a scale comprising a beam and a rotary indicator, a pinion upon the shaft of the latter, a rack rod connected to said beam and comprising a flattened extension, a rack suspended from the upper end of said extension and meshing with the pinion and means for yieldingly holding the rack and pinion in mesh.

5. In a scale having a beam and a rotary indicator, a pinion upon the shaft of said indicator, a rocker pivoted to the beam and over-weighted on one side, a spring connected to the rocker, a rack rod to which the other end of the spring is connected and a rack depending from the upper end of said rack rod and engaging said pinion.

6. In a scale and in combination with the beam and indicating means thereof, an actuating rod for the latter attached to the beam, the attaching means comprising a weighted casting connected to the rod, a seat plate connected to the casting and having oppositely directed seats, a knife plate secured to the beam and having oppositely directed knives engaging the seats on said seat plate.

7. In a weighing scale and in combination with the beam and indicator thereof, connections between the same including a knife plate on the beam having terminal knife edges facing in one direction and an intermediate edge facing in the opposite direction, a seat plate having downwardly turned ends engaging the terminal knife edges on the knife plate and an intermediate tongue carrying a seat for engaging the intermediate knife edge and a rod carried by said seat plate.

8. In a weighing scale and in combination with the beam and rotary indicator thereof, connections between the same including a connecting rod, a knife plate on the beam having upwardly directed terminal edges and a downwardly directed intermediate edge, a seat plate having downwardly turned ends adapted to rest upon the terminal edges of the knife plate an intermediate tongue on the seat plate extending beneath the intermediate edge on the knife plate, an adjustable screw mounted on said tongue and adjustable beneath the inter-

mediate knife edge and connections from said plate to said connecting rod.

9. In a scale having a beam and a rotary indicator, a pinion on the latter, a rack rod supporting a depending rack engaging said pinion, a spring supporting said rack rod, a rack member to which said spring is attached, a seat plate attached to said member having downwardly turned ends provided with knife seats and an intermediate tongue provided with an upwardly extending knife seat, and a knife plate upon the beam comprising upwardly directed terminal knives and a downwardly directed intermediate edge engaging the knives on the seat plate.

10. In a weighing scale, a check device comprising a stationary post and a check rod, knife plates arranged on said post and rod respectively, one of the knife edges on each plate being directed toward the other plate and the other of said knife edges on each plate being directed away from the other plate, a spacing bar extending between the first named pair of knife edges and a connecting link embracing the second pair of knife edges.

11. In a weighing scale, a check device comprising a stationary post and a check rod, knife plates arranged on said post and rod respectively, one of the knife edges on each plate being directed toward the other plate and the other of said knife edges on each plate being directed away from the other plate, a spacing bar extending between the first named pair of knife edges and a connecting link embracing the second pair of knife edges and means for pivoting said bar and plate together.

12. In a weighing scale, a check rod 25, a check post 27, knife plates 85 secured to the lower ends of the check rod and check post respectively and having inwardly directed knife edges 87 and outwardly directed knife edges 88, a thrust member 89 between the knife edges 87 and a perforated link 91 engaging knife edges 88, a pivot connecting the thrust member and link and a spacing sleeve 95 surrounding said pivot.

13. In a weighing scale comprising a beam and a load-offsetting means, connections between said means and beam comprising a knife edge on the beam, a stirrup member 106 connected to the load-offsetting means and formed with a socket in its end, a frame, a bearing block for the knife edge 120 mounted in the frame, and a shank on the frame extended into the socket on the stirrup member.

14. In a weighing scale having a beam and a load-offsetting means, connections between said members including a knife edge upon the beam, a stirrup member having a split lower end, a longitudinal socket in said end, a frame, a bearing block for the knife edge carried by the frame, a shank con-

- 5 nected to the frame and extending into the socket in the stirrup member, and means for drawing the ends of the split stirrup member together to clamp the shank in the 5 socket.
15. In a weighing machine comprising a beam and a load-offsetting means, connections for said members comprising a knife edge upon the beam, a stirrup member, a 10 frame, a bearing block for the knife edge supported in the frame, a shank upon the frame having a threaded end, there being a socket in the lower end of the stirrup member tapped for a portion of its length to receive 15 said shank, said stirrup member split at its lower end, and means for drawing the sections thereof together to clamp the shank.
16. In a weighing machine of the class described comprising a beam and a load offsetting means, connections between the two comprising a knife edge upon the beam, a frame having downwardly extending legs, a trough mounted between the legs, a bearing block mounted in the trough and adapted 20 to receive the knife edge upon the scale beam.
17. In a scale of the class described comprising a beam and a load-offsetting means, connections between these two elements in- 25
- cluding a frame 109 having downwardly extending legs 116—116, a trough 118 having a transverse corrugation 120, an agate 121 mounted in the trough and receiving the knife edge and a stop for limiting the play of the beam end in the frame. 30
18. A weighing scale comprising a beam, a rotary indicator, a pinion upon the shaft of said indicator, a rack-rod connected to the beam, a depending rack carried by said rack-rod and extending into engagement with the pinion, and means for vertically adjusting the position of the depending rack upon the rack-rod. 35
19. A weighing scale comprising a beam, a rotary indicator mounted above the beam, 40 a pinion upon the shaft of said indicator, a rack-rod connected at its lower end to said beam and having a lateral extension at its upper extremity, a depending rack loosely mounted upon said lateral extension of the 45 rack-rod and extending into engagement with the pinion, and means for vertically adjusting the position of the depending rack upon the rack-rod.
